UNITED STATES PATENT OFFICE.

NORMAN CRAIG FETTERS, OF ALLIANCE, OHIO, ASSIGNOR TO WILLIAM H. MORGAN,
OF ALLIANCE, OHIO.

MEANS FOR SECURING RAILS TO METAL TIES.

1,053,801.

Specification of Letters Patent. Patented Feb. 18, 1913.

Application filed June 12, 1912. Serial No. 703,341.

To all whom it may concern:

Be it known that I, NORMAN C. FETTERS, a citizen of the United States, residing at Alliance, in the county of Stark and State 5 of Ohio, have invented certain new and useful Improvements in Means for Securing Rails to Metal Ties; and I do hereby declare the following to be a full, clear, and exact description of the invention, such as will 10 enable others skilled in the art to which it appertains to make and use the same.

My invention relates to an improvement in means for securing rails to metal ties, and is designed particularly as an improvement 15 on the construction disclosed in U. S. Patent No. 1,026,108 granted to W. H. Morgan, May 14th, 1912.

In the patent, the lower ends of the elastic clamps which secure the rails to the ties are 20 held in place by the engagement with ribs on ribbed plates, referred to as armor plates, which rest against insulating material on the lower face of the top flange of the tie.

The object of my invention is to so construct the armor plate that it carries and supports its insulation.

It further consists in the details of construction of said armor plate as will be more fully described and pointed out in the 30 claims.

In the accompanying drawings, Figure 1 is a view in section through a rail and its support showing my improved armor plate and its insulation. Figs. 2 and 3 are perspective views of the armor plate and Figs. 4 and 5 are similar views of the armor plate 35 insulators.

The tie 1 is made of metal, preferably I-shape in cross section with its base flange 40 wider than its top flange; 2 is the chair having downwardly projecting flanges 3 to embrace the opposite side edges of the top flange of the tie, and upwardly projecting flanges 4, to engage the side edges of the 45 base flange 5 of the rail 6; 7 is the insulation interposed between the chair and the top of the tie, and 8 are the spring metal clamps which secure the rails in place. All of the 50 above parts are disclosed in the Morgan patent above referred to.

9 is the armor block or plate. These blocks or plates may each be of a length sufficient to be engaged by all the clamps on one side of the tie, but I prefer to make one for each

clamp, each block being slightly longer than 55 the clamp is wide, so as to project at both sides beyond the latter. Each block is provided on its outer face with a depending rib 10 against the rear side of which the lower free end of the spring clamp abuts. These 60 ribs are located nearer to one edge of the block than the other, so that by reversing the position of the blocks on the opposite sides of the tie, as shown in Fig. 1 the upper free 65 ends of the clamps will bear at points equidistant from the vertical center of the rail. As shown in the drawing, and as disclosed in the patent above referred to, the chair 2 is so constructed that when the parts are assembled, the vertical center of the rail will be to 70 one side of the vertical center of the tie. By changing the position of the chair end for end, the center of the rail will be shifted to the opposite side of the center of the tie. If, when the chair is so changed the blocks 9 75 should remain as they are, it will be seen that the clamps at one side would overlap the base flange of the rail more than the clamps at the other side, and bear with unequal pressure at opposite sides of the rail, hence 80 by shifting the blocks end for end, the clamps are made to bear at equal distances from the vertical center of the rail. Each block 9 is also provided with the end flanges 11, which however do not project beyond the 85 plane of the rib, but which together with the central rib 10 form recessed seats for the reception of the lower ends of the spring clamps 8.

The armor or block 9 is preferably cast or 90 drop forged, and is hollow and open on its upper side as shown in Fig. 3, so that the insulation 12 which fills the same, may project at the two sides and ends so as to prevent any contact between the block and the 95 tie. The insulation 12, may be a block of wood shaped to conform to the hollow block, or any other insulating material molded or shaped to conform to the block may be used, or an insulating compound may be molded 100 directly into the block so as to be a part thereof. In any event it should project sufficiently beyond the block 9 and is preferably provided with a lip 13 around its four sides so as to absolutely prevent any contact between the block and the tie, or part against which the block is supported.

It is evident that many slight changes

might be resorted to in the relative arrangement of parts shown and described without departing from the spirit and scope of my invention. Hence I would have it understood that I do not wish to confine myself to the exact construction and arrangement of parts shown and described, but—

Having fully described my invention what I claim as new and desire to secure by Letters Patent, is—

- 10 1. An armor block for rail securing devices having a rib intermediate its side edges and flanges at its ends, the ribs and flanges forming recessed seats.
- 15 2. A hollow armor block for rail securing devices having an external recessed seat, and insulating filling for said block, the said filling projecting outside of the block so as to prevent contact between the latter and the tie.
- 20 3. A hollow armor block for rail securing devices having an external recessed seat,

and an insulating filling conforming in shape to the inside of the block.

4. A hollow armor block for rail securing devices having an external seat and a removable insulating filling shaped to conform to the inner surface of the block.

5. A reversible armor block for rail securing devices having two recessed seats.

6. A reversible armor block for rail securing devices having two recessed seats one of said seats being of greater width than the other.

7. A reversible armor block for said securing devices having two recessed seats and an insulating filling.

In testimony whereof I have signed this specification in the presence of two subscribing witnesses.

NORMAN CRAIG FETTERS.
